UNITED STATES PATENT OFFICE.

HILMER F. RODLER, OF DAVENPORT, IOWA, ASSIGNOR TO CALVIN J. MUMMERT, OF WEST NEW YORK, NEW JERSEY.

VALVE.

Application filed May 14, 1926. Serial No. 109,140.

While this invention is concerned broadly with improvements in the construction and operation of valves, it is more especially concerned with improvements in means for controlling the flow of gas for producing the igniting flame in oil burner mechanism and among the objects thereof are to produce a self-cleaning valve; to produce a perfect seating valve; to produce a valve which seats with a rotary motion whereby the valve seat and valve closure member are kept clean and a perfect closure is always assured; to provide improved mechanism for imparting rotary and reciprocatory motion to a valve closure member; to provide a device of the class described which will invariably function to produce the result desired; to produce a device of the character indicated in which resistance to movement of the parts will be reduced to a minimum; and such further objects, advantages, and capabilities as will hereafter appear and as are inherent in the construction disclosed herein.

My invention further resides in the novel features of construction and operation herein illustrated and described and, while I have shown in the drawing what is now considered the preferred embodiment of my invention, I desire the same to be understood as illustrative only and not as limiting said invention.

In the drawing annexed hereto and forming a part hereof, Fig. 1 shows a longitudinal section through the body of my new construction, parts thereof being shown in elevation; Fig. 2 is a transverse section substantially along the plane indicated by broken lines 2—2, Fig. 1; Fig. 3 is an elevation of the valve closure means and cam, as viewed from the right side as shown in Fig. 1; and Figs. 4 and 5 are views similar to Fig. 3 showing the valve controlling cam in other positions.

Referring more in detail to the annexed drawing, numeral 1 designates a hollow body having inlet and outlet ports 2 and 3, said ports being connected by a channel 4 having an opening 5 therein which may be closed entirely or partially by the valve closure member 6. This valve closure member is carried axially by the cam 7 and seats accurately at 8 so as to entirely close the opening 5.

Projecting axially from the opposite face of the cam 7 is a body member 9 carrying projections 10 which cooperate with the driving mechanism to produce rotary motion of the cam, which in turn produces axial movement

of the valve closing member 6. A shaft 11 extending from suitable driving means passes through the stud 12 whereby the valve is secured to any desired supporting member 13. In the present instance this is a part of the supporting or encasing means for the entire structure. The shaft 11 has a head 14 detachably secured to the inner end thereof, preferably by means of a set screw 15. This head carries projections 16 which cooperate with the projections 10 to cause rotary motion of the cam 7, as outlined above. Because of the shape and material of the projections 10 and 16 friction at the points of contact thereof is reduced to a minimum, so that there shall be the least possible resistance to the sliding or axial movement of the parts. The head 14 is preferably hollowed out for the reception of resilient means 17, shown in the present instance as a spring, and this resilient means presses against the projection 9 to constantly keep the cam 7 seated against the various abutments with which it cooperates, and to cause seating of the valve closure means 6, when the valve is supposed to be closed. The head 14 is longitudinally apertured, as shown at 18, for the reception of the shaft 11 and the projection 19 which extends axially with relation to the valve closure member 6, the cam 7 and the projection 9. As shown, the end of member 19 is bevelled to cooperate with a corresponding bevel at the end of opening 18, so that the projection 19 will be sure to enter the opening 18, when movement of cam 7 causes retraction of valve closure member 6. This assists in keeping the parts in axial alignment and thus reducing wear.

An adjustable member 20 extends through the body member 1 and serves to open the valve sufficiently to permit a regulated amount of gas to flow therethrough for supplying an igniting flame. As the cam 7 turns in the direction indicated by the arrow in Fig. 3, the portion 26 of the cam rides on the inner end of screw 20 and the valve is thereby maintained in a slightly opened position. The cam rides around on the end of this screw until cam face 22 strikes projection 23, as shown in Fig. 4, when the valve is opened wide to permit a large flow of gas through the valve to the burner to ignite the oil when admitted. The cam then continues its rotation until shoulder 24 passes projection 23 as shown in Fig. 5, when the valve is permitted to close completely. In this position

the screw 20 is out of contact with the cam. In the meantime the fluid fuel has been ignited by the burning gas and will continue to burn until the supply of fuel is shut off. Just 5 before the oil valve closes cam face 21 engages screw 20 and causes the opening, slightly, of the gas valve, the gas being ignited from the oil flame. The cam 7 continues its rotation until cam face 22 approaches projection 23, when the valve ceases rotation and is 10 maintained in slightly open position to keep the gas burning, adjusted to a small flame, until the next cycle of operation begins.

It is of course understood that specific 15 description of structure set forth herein may be departed from without departing from the spirit of my invention as set forth herein and expressed in the appended claims.

Having now described my invention, I 20 claim:

1. In a valve, a body member having a fluid 25 passage therethrough provided with a valve seat, a valve member therein for cooperating with the said seat to close the passage, said valve member being capable of rotating continuously in one direction throughout a complete cycle, a cam rigidly connected with said valve member and capable of moving the same longitudinally when actuated, said cam 30 through a part of its cycle permitting said valve to close completely, means on the valve body to cooperate with said cam to open the valve completely or permit it to partly or entirely close, and separate means to maintain 35 the valve partly open through a portion of its cycle when released from the control of the valve opening means.

2. In a valve, a body member having a fluid 40 passage therethrough provided with a valve seat, a valve member therein for cooperating with the said seat to close the passage, said valve member being capable of rotating continuously in one direction throughout a complete cycle, a cam rigidly connected with said 45 valve member and capable of moving the same longitudinally when actuated, said cam through a part of its cycle permitting said valve to close completely, means on the valve body to cooperate with said cam to open the valve completely or permit it to partly or entirely close, and adjustable means to maintain 50 the valve partly open through a portion of its cycle when released from the control of the valve opening means, and providing for regulation of the size of the opening in the partially opened position.

3. In a valve, a body member having a fluid 55 passage therethrough provided with a valve seat, a valve member therein for co-operating with the said seat to close the passage, a cam rigidly connected with said valve member and capable of moving the same longitudinally when actuated, separate means carried by said body to cooperate with said 60 cam for opening said valve partly and en-

tirely respectively and holding same so opened during a portion of the actuation of the cam, one of said means being adjustable to vary the size of the opening.

4. In a valve having a body provided with a fluid opening therethrough and a closure member to close said opening, said closure member being rotatable about its axis; an actuating member rotatable substantially co-axially with said closure member, interengaging projections on the actuating and closure members engaging each other in slidable relation, means for moving said closure member toward the actuating member when the closure member is rotated, and resilient means tending to force the closure member away from the actuating member. 70

5. In a gas valve having a body through which extends a channel adapted to be opened and closed by a valve member, a valve member for opening and closing said channel, a cam connected to said valve member, means for rotating said cam, means to reciprocate the cam so as to open the valve slightly and other means functioning on the rotation of the cam 80 to cause reciprocation of the valve closure means into fully opened position. 85

6. In a valve operating mechanism, a rotary cam for reciprocating a valve closure member, said cam having projections extending laterally therefrom, a driving member rotatable co-axially with the cam, said driving member having projecting members co-acting with the projections on the cam to form a driving connection between said cam and said 90 driving member, and means cooperating with said cam to cause reciprocation thereof. 95

7. In a valve operating mechanism a body member having a channel extending therethrough and a closure member adapted to open and close said channel, a cam for actuating said closure member, a rotary driving member having projections extending therefrom toward the cam, projections carried by the cam and adapted to co-act with the projections on the driving member to form a driving connection between the two and to permit relative axial movement between the cam and driving member, and means cooperating with said cam to cause reciprocation 100 thereof. 105

8. In a valve operating mechanism a body member having a channel extending therethrough and a closure member adapted to open and close said channel, a cam connected to said closure member, a rotary driving member having projections extending therefrom toward the cam, projections carried by the cam and adapted to co-act with the projections on the driving member to form a driving connection between the two and to permit relative axial movement between the cam and driving member and means for moving the cam axially during its rotation for actuating 110 said closure member. 115

9. In a valve operating mechanism a body member having a channel extending therethrough and a closure member adapted to open and close said channel, a cam connected to said closure member, a rotary driving member having projections extending therefrom toward the cam, projections carried by the cam and adapted to co-act with the projections on the driving member to form a driving connection between the two and to permit relative axial movement between the cam and driving member, means for moving the cam axially in one direction during a portion of its rotation and resilient means for moving said cam axially in the opposite direction at another point in its rotation for actuating said closure member.
10. In a valve operating mechanism, a hollow body member in which a cam is mounted for rotary and axial movement, a valve member carried by said cam, projections extending from said cam and adapted to cooperate with a rotary member to transmit rotary motion to the cam, a rotary member in said hollow body having projections therefrom adapted to cooperate with the projections on the cam, a spring adapted to cause separation of the rotary member and the cam, and means to cause movement of the cam toward the rotary member during a part of the cycle of rotation thereof. 20 25 30

In witness whereof, I hereunto subscribe my name to this specification.

HILMER F. RODLER.
